(57) **CLAIM**

The ornamental design for a contoured gel pack with directional drainage channels, as shown and described.

DESCRIPTION

FIG. 1 is a front right perspective view of a contoured gel pack with directional drainage channels showing my new design;

FIG. 2 is a front left perspective view thereof;

FIG. 3 is a rear right perspective view thereof;

FIG. 4 is a rear left perspective view thereof;

FIG. 5 is a front view thereof;

FIG. 6 is a left side view thereof;

FIG. 7 is a right side view thereof;

FIG. 8 is a top view thereof; and,

FIG. 9 is a bottom view thereof.
